Primary Examiner — Sandra Snapp*Assistant Examiner* — Donald B Rose, Jr.(74) *Attorney, Agent, or Firm* — Reinhart Boerner Van Deuren P.C.(57) **CLAIM**

I claim the ornamental design for a pocket hole jig, as shown and described.

DESCRIPTION

FIG. 1 is a top perspective view of the pocket hole jig; FIG. 2 is a further top perspective view thereof; FIG. 3 is a further top perspective view thereof; FIG. 4 is a further top perspective view thereof; FIG. 5 is a bottom perspective view thereof; FIG. 6 is a further bottom perspective view thereof; FIG. 7 is a rear view thereof; FIG. 8 is a front view thereof; FIG. 9 is a side view thereof; FIG. 10 is a side view thereof showing the side opposite that shown in FIG. 9; FIG. 11 is a top view thereof; and, FIG. 12 is a bottom view thereof. The broken lines depict portions of the pocket hole jig that form no part of the claimed design.
